ROOF FRAMER

James D. Lawrence, Woodson, Ark.

Application June 2, 1950, Serial No. 165,615

3 Claims. (Cl. 33—94)

1

This invention relates to an improved device for roof framing and the like, the primary object of the invention being to provide a simple device of this kind with the use of which an inexperienced carpenter can easily and quickly lay out and frame a slanting roof by obtaining from simple adjustments of the framer, the top cuts, bottom cuts, and lengths of common, hip, and valley rafters, and the bevel and lengths of jack rafters, without performing any mathematical calculations, and which can also be used for laying out stairways and the steps thereof.

Another important object of the invention is the provision of a device of the character indicated above which is composed of only two relatively movable and simply constructed parts, which can be manufactured in a rugged and serviceable form at relatively low cost.

Other important objects and advantageous features of the invention will be apparent from the following description and the accompanying drawings, wherein, merely for illustrative purposes, a specific embodiment of the invention is set forth in detail.

In the drawings:

Figure 1 is a plan view of the illustrated device, showing the triangle set for a framing operation.

Figure 2 is a fragmentary vertical longitudinal section taken on the line 2—2 of Figure 1.

Figure 3 is a plan diagram of lengths of common rafters on the base.

Figure 4 is a plan diagram of lengths of valley rafters on the base.

Referring in detail to the drawings, the numeral 5 generally designates the base of the device, which is in the form of a flat elongated rectangular plate having a straight functional edge 6. Extending toward the right from its left hand end the edge 6 has a scale 7 marked with 24 one-inch graduations 8 divided by sixteenth inch graduations 9. Beginning at the 15½ inch mark 10 with the numeral "5," the scale 7 has half-inch graduations or marks 10' running to "16," ending at the 21-inch mark, as indicated at 11. The numerals from "5" to "16" relate to one-half of the width of the building whose roof is to be framed.

Extending parallel to the edge 6 from the inch graduation "1" to the inch graduation "11" is a slot 12. At each end of the edge 6 is a lug 13 projecting beyond the edge 6 to support the base 5 with the edge 6 parallel with the material while laying out the work.

The triangle 14, which is positioned upon the base 5, is an open isosceles right triangular flat plate formed with a hole 15 aligned with the cen-

2

ter of the acute angle at the left hand corner of the triangle, and also with a slot 15' beginning ¾" from hole 15 and extending three inches parallel to edge of the blade 18. A headed bolt 16 which passes through the slot 12 of the base 5 is adapted to be passed either through the hole 15 or the slot 15'. A knurled nut 17 is provided on the bolt to enable clamping the base and triangle in selected relative positions when desired, the bolt 16 serving as a pin slidable along the slot 12 to guide longitudinal and pivotal movement of the triangle 14 relative to the base 5.

The left hand or base side 18 of the triangle constitutes the "blade," the right hand or altitude side 19 the "tongue" and the lower or hypotenuse side 20 the "brace" of the triangle 14. The "brace" is formed intermediate its ends with a tilted window slot 21 and the lower end of the "tongue" is provided with a similarly tilted window slot 22, these window slots being registrable with areas of the base 5 as hereinafter described. The outer edges of the blade 18 and tongue 19 are each provided with one-inch markings 18' and 19', respectively, having sixteenth inch subdivisions beginning at the corners of the triangle.

The area "A" is composed of lines of rectangular boxes 23 containing figures 24 representing lengths of common rafters, the slot 21 of the brace 20 of the triangle 14 being registrable with any one of the boxes 23. To the right of the area "A" is the area "B" consisting of similar lines of boxes 25 containing figures 26 representing lengths of valley rafters.

Along the right hand or outer edge 27 of the tongue 19 is a scale of equal graduations 28 numbered from 4 to 12 to indicate the rise per foot of span of common rafters. An intermediate column of equal graduations 29, staggered with respect to the graduations 28, is located inwardly of the first mentioned column and indicates the rise per foot of valley rafters. An inner column of graduations 30, shorter than the other columns but also numbered from 4 to 12 indicates bevel cut for jack rafters. The intermediate graduations 29 indicate the rise per foot of span of valley rafters while the inner graduations 30 indicate the bevel cut for jack rafters.

The graduations 28 and 29 extend to the outer blade edge 27, the graduations 29 being angularly deflected to line up with the graduations 11 on the half-length scale on the base 5. When so lined up, the edge 27 of the tongue provides a straight edge for marking the top cut on the timber and outer edge 18' of the blade provides a straight edge for marking the bottom cut. The

figure 26 in the box 25 in the right hand area "B" on the base exposed by the tongue window slot 22 will then be the proper length of the valley rafters; and the figure 24 in the box 23 of area "A" exposed in the brace window slot 21 will be the proper length of common rafter.

The proper rise per foot of span is determined by placing the end of the proper graduation 30 of the inner column on the tongue 19 under the desired rise with the edge 6 of base 5 and marking along the edge 18' of the blade 18, whereby the proper bevel cut for the jack rafters is obtained.

The triangle 14 is originally placed relative to the base 5, where the building to be roof framed is 28 feet wide, with a rise of 8 inches per horizontal foot of span, by placing the triangle on the base so that the figure 8 in the right hand or outer column of graduations 28 on the tongue 19 is aligned with the 20 inch mark on the base edge 6, corresponding to the 14 mark on the half inch scale 11.

The top or plumb cut is obtained by marking the timber along the outer edge 19' of the tongue and the bottom or horizontal cut by marking the timber along the outer edge 18 of the blade. By looking through the brace window 21 the length of 16 feet 10 $\frac{1}{8}$ inches is found as the proper length for the common rafters.

For hip or valley rafters, the triangle 14 is placed on the base 5 so that the graduation 29 corresponding to a rise of 8 inches is aligned with the graduation 11 on the edge 6 of the base corresponding to 14 or one-half of the building width. The marking is then done along the outer edges of the tongue 19 and blade 18 as in the case of common rafters to obtain the top and bottom cuts for the valley rafters. By looking through the slot 22 of the tongue 19 the figure 22 feet 10 $\frac{1}{8}$ inches is seen which is the proper length of the hip or valley rafters.

The triangle 14 is then shifted to place the graduation 30 of the inner column on the tongue 19, corresponding to a rise of 8 inches, in alignment with the edge 6 of the base 5. Marking the timber along the outer edge of the blade 18 gives the bevel cut for the jack rafters. The information box 31 on the blade then gives the proper length for the jack rafters.

To lay out steps of a stairway the outer edge 32 of the blade 18 is used for the width of the treads and the outer edge 27 of the tongue 19 is used for the risers. If steps of narrower than standard tread are to be laid out, the bolt 16 is put through the slot 15 in the blade instead of the hole 15.

What is claimed is:

1. In a roof framing device, an elongated base plate having a straight longitudinal edge on one side thereof, a single longitudinal slot formed in said base plate parallel to and close to said straight edge, a right triangle overlying said base plate, said triangle having base, altitude, and hypotenuse sides, said triangle having its hypotenuse side overlying the base plate and portions of its base and altitude sides extending beyond the straight edge of the base plate, a clamping bolt extending through said longitudinal slot and journaled in the corner of the triangle at which its base and hypotenuse sides meet whereby movement of said triangle is limited to longitudinal movement along and pivotal movement about said base plate to present edges of said base and altitude sides as marking edges in conjunction with said straight edge said longitudinal slot reaching from one end of said base plate to a point in longitudinally spaced relation to the

other end of the base plate and having a longitudinally inward end, the surface of said base plate between the longitudinally inward end of the slot and the said other end of the base having two longitudinally spaced groups of boxes thereon, the hypotenuse side of the triangle constituting a brace, the base side thereof a blade, and the altitude side thereof a tongue, said base having a window formed therein for selective registry with one group of boxes and said tongue having a window formed therein for registry with the other group of boxes.

2. In a roof framing device, an elongated base plate having a straight longitudinal edge on one side thereof, a single longitudinal slot formed in said base plate parallel to and close to said straight edge, a right triangle overlying said base plate, said triangle having base, altitude, and hypotenuse sides, said triangle having its hypotenuse side overlying the base plate and portions of its base and altitude sides extending beyond the straight edge of the base plate, a clamping bolt extending through said longitudinal slot and journaled in the corner of the triangle at which its base and hypotenuse sides meet whereby movement of said triangle is limited to longitudinal movement along and pivotal movement about said base plate to present edges of said base and altitude sides as marking edges in conjunction with said straight edge said longitudinal slot reaching from one end of said base plate to a point in longitudinally spaced relation to the other end of the base plate and having a longitudinally inward end, the surface of said base plate between the longitudinally inward end of the slot and the said other end of the base having two longitudinally spaced groups of boxes thereon, the hypotenuse side of the triangle constituting a brace, the base side thereof a blade, and the altitude side thereof a tongue, said base having a window formed therein for selective registry with one group of boxes and said tongue having a window formed therein for registry with the other group of boxes.

3. In a roof framing device, an elongated base plate having a straight longitudinal edge on one side thereof, a single longitudinal slot formed in said base plate parallel to and close to said straight edge, a right triangle overlying said base plate, said triangle having base, altitude, and hypotenuse sides, said triangle having its hypotenuse side overlying the base plate and portions of its base and altitude sides extending beyond the straight edge of the base plate, a clamping bolt extending through said longitudinal slot and journaled in the corner of the triangle at which its base and hypotenuse sides meet whereby movement of said triangle is limited to longitudinal movement along and pivotal movement about said base plate to present edges of said base and altitude sides as marking edges in conjunction with said straight edge said longitudinal slot reaching from one end of said base plate to a point in longitudinally spaced relation to the other end of the base plate and having a longitudinally inward end, the surface of said base plate between the longitudinally inward end of the slot and the said other end of the base having

two longitudinally spaced groups of boxes thereon, the hypotenuse side of the triangle constituting a brace, the base side thereof a blade, and the altitude side thereof a tongue, said brace having a window formed therein for selective registry with one group of boxes and said tongue having a window formed therein for registry with the other group of boxes, said straight edge of the base plate having longitudinal graduations of equal length therealong and an edge of the tongue of the triangle having longitudinal graduations adapted to be aligned with the graduations of the straight edge, whereby the windows of the brace and tongue become registered with predetermined boxes of the groups of boxes, the blade of the triangle being formed with a slot parallel to the outer edge of the tongue through which said bolt passes so that the triangle can be moved relative to the bolt so as to change

the pivotal point of said triangle on the base plate.
